(57) **CLAIM**

The ornamental design for an apparatus for a video game system, as shown and described.

DESCRIPTION

FIG. 1 is a front perspective view of an apparatus for a video game system showing our new design;

FIG. 2 is a front elevational view thereof;

FIG. 3 is a top plan view thereof; and,

FIG. 4 is a right side elevational view thereof.

The broken lines are for illustrative purpose only and form no part of the claimed design.
